UNITED STATES PATENT OFFICE.

RALPH L. MORGAN, OF WORCESTER, MASSACHUSETTS.

METHOD OF MAKING DIES.

Application filed October 12, 1923. Serial No. 688,082.

To all whom it may concern:

Be it known that I, RALPH L. MORGAN, a citizen of the United States, residing at Worcester, in the county of Worcester and State of Massachusetts, have invented a new and useful Method of Making Dies, of which the following is a specification.

This invention relates to dies such as are commonly used in wire drawing operations. 10 Such dies are made of hard metal with a tapered hole therein, which at its smaller end is of the exact size of the wire to be drawn. Such dies are subject to very severe wear when in use, particularly when 15 the wire is not fully cleaned of dirt and scale, and the dies require frequent re-dressing to restore them to their correct size.

It is the object of my invention to provide an improved method by which such dies 20 may be economically and accurately restored to size, and by which new dies may be manufactured if desired. While particularly applicable to wire drawing dies, it will be understood that the invention is not necessarily limited to use with this particular kind of die.

For a more complete disclosure of my invention, I have indicated in the drawings a form of mechanism by which my improved 30 method or process may be conveniently carried out.

Fig. 1 of the drawings is a side elevation of a drop hammer, together with certain attachments adapting the same to my purposes;

Fig. 2 is a plan view of the die holder shown in Fig. 1; and

Fig. 3 is an enlarged sectional view of a worn die before re-dressing.

Referring to the drawings, I have indicated parts of a drop hammer of a usual commercial type, comprising a frame 10, a weight or head 11, a lifting board or bar 12 secured to the upper end of the weight 11, driven rolls 13 and 14 for raising the weight, and a knee or bracket 15 for supporting the work. All of these parts, together with suitable mechanism (not shown) for rotating the driven rolls and for moving them 45 toward and from each other, may be of the usual construction and in themselves form no part of my invention.

A die holder 16 is pivoted at 17 on the bracket 15 and comprises two jaws which 50 may be held in closed position by a ring 18

fitting over the handles or extensions 19. A block 20 limits inward movement of the jaws and centers the same accurately on the bracket or support 15.

A mandril 21 is slidable vertically in an opening or passage in the bracket 15 and is centrally disposed with respect to the opening in the holder 16. A pair of toggle arms 22 and 23 are mounted below the mandril 21, these arms being pivoted to each other at 24 and the lower arm 23 being formed as a portion of a bell crank having also a foot lever or pedal portion 25. The upper arm 22 is pivoted at 26 to the lower end of the mandril and a spring 27 tends to straighten the toggle against a stop pin or stud 28. When the pedal 25 is depressed, the toggle is broken and the mandril is drawn downward.

A die block 30 is secured in the lower surface of the weight or head 11 and is concavely shaped to correspond to the upper face of a wire drawing die D. The general construction of the die D is clearly shown in Fig. 3, which also indicates at 31 the wear which takes place during the wire drawing operation.

Having described the mechanism shown in the drawings, I will now explain my new method or process of shaping or re-dressing dies. For this purpose, the die D is first heated until the metal is sufficiently softened so that it can be re-distributed under pressure. The die is then dropped over the upper end of the mandril 21, which is held in the fixed raised position indicated in Fig. 1. The holder 16 is then clamped firmly about the die and the head 11 is allowed to drop upon the upper surface thereof.

Contact of the concave block 30 with the upper face of the die D forces the heated metal downward and inward against the upper end of the mandril and causes the die to conform exactly to the outline thereof. Outward expansion is prevented by the holder 16. The mandril is then quickly withdrawn by depressing the pedal 25 and the re-formed die D is transferred to a suitable cooling and hardening bath.

It is desirable that the surface of the mandril be coated with graphite or other lubricant before the die is placed thereover. This lubricant delays the transfer of heat to the mandril and will also give off smoke and combustion gases which will largely

prevent oxidation of the die while it is being shaped and transferred to the cooling and tempering bath.

It is thus seen that my improved method or process enables me to accurately shape or re-shape wire drawing and other dies with a minimum expenditure of time and labor and with absolutely accurate and identical results in successive dies. Furthermore, the fact that oxidation is prevented leaves the wire drawing passage in the die smooth and in the best possible condition for drawing wire.

Having thus described my invention and the advantages thereof, I do not wish to be limited to the details herein disclosed otherwise than as set forth in the claims, but what I claim is:—

1. The method of forming a die which consists in heating the die, placing an accurately sized mandril within the hole in the die, firmly compressing the die about the mandril while the mandril is thus positioned, and thereafter withdrawing said mandril.

2. The method of forming a die which consists in heating the die, placing an ac-

curately sized mandril within the hole in the die, compressing the material of the die about the mandril while the mandril is thus positioned, promptly separating the die and mandril, and thereafter hardening the die.

3. The method of forming a die which consists in heating the die, placing an accurately sized mandril within the hole in the die, holding the die from radial expansion and striking the die a heavy blow in an axial direction to force the material of the die against the mandril while the mandril is thus positioned, said blow also firmly 40 and simultaneously compressing said material.

4. The method of forming a die which consists in heating the die, coating an accurately sized mandril with lubricant, placing the coated mandril within the hole in the die, compressing the material of the die about said mandril while the mandril is thus positioned, and thereafter separating said die and mandril, the combustion of the 50 lubricant preventing oxidation of the die.

In testimony whereof I have hereunto affixed my signature.

RALPH L. MORGAN.
